UNITED STATES PATENT OFFICE.

MORRIS A. BARR, OF ARDMORE, PENNSYLVANIA.

QUICK-CHANGE MACHINE.

1,238,083.

Specification of Letters Patent. Patented Aug. 28, 1917.

Application filed April 30, 1917. Serial No. 165,428.

To all whom it may concern:

Be it known that I, MORRIS A. BARR, a citizen of the United States, residing at Ardmore, in the county of Montgomery and State of Pennsylvania, have invented certain new and useful Improvements in Quick-Change Machines, of which the following is a specification, reference being had to the accompanying drawings.

10 This invention relates to means for dispensing coins and particularly to means for dispensing coins for change.

The general object of this invention is to provide a very simple, readily operated and 15 effective machine of this character whereby coins from a stack of coins may be discharged onto a table at the will of the operator, means being provided on the table whereby a proper number of coins may be 20 withdrawn from the table according to the amount desired by the operator.

A further object of the invention is to provide a machine of this character including a coin receiving table and a reciprocable 25 coin holder movable over the face of the table and holding a stack of coins, the arrangement being such that on a rearward movement of the coin holder, a series of coins will be laid flat down upon the table, 30 one behind the other and upon a forward movement of the holder, the coins will be pushed forward so as to again fill up the table.

A further object of the invention in this 35 connection is to provide means for preventing the superposition of one coin upon another as the coin holder is moved rearward, said means being preferably adjustable, so that the machine may be used with coins 40 of different thicknesses and different values.

A further object is to provide adjustable means, which will engage the rearmost coin of a line of coins, so that when the holder is moved forward, the lowermost coin of the 45 stack of coins will be carried forward with the holder so as to be left at the forward or discharge end of the table.

Other objects will appear in the course of the following description.

50 My invention is illustrated in the accompanying drawings, wherein:—

Figure 1 is a longitudinal sectional view of a coin dispensing apparatus of the character described, the section being taken on the line 1—1 of Fig. 2, the coin holder, how-

ever, being broken away at its rear end and being partly in section;

Fig. 2 is a top plan view of the construction illustrated in Fig. 1;

Fig. 3 is a fragmentary sectional view on the line 3—3 of Fig. 1 looking in the direction of the arrows.

Referring to these drawings, 10 designates a base or table of any suitable dimensions, and which is provided at spaced intervals with the longitudinally extending guide walls 11, defining coinways 12. These guide walls are spaced at different distances from each other so that the guideways will have different widths, according to the denomination of the coins to be discharged. I have illustrated in the drawings, the base as formed with four guideways, *a*, *b*, *c* and *d*, it being understood, however, that a greater number of guideways may be used or a less 70 number. The guideway *a* is illustrated as holding pennies, the guideway *b* as holding five cent pieces, the guideway *c* as holding ten cent pieces, and the guideway *d* as holding twenty-five cent pieces. This, of course, 75 is purely illustrative.

Each of the walls 11 is provided with inwardly extending grooves 13 on its opposite faces and at the rear end of the base there is provided the transversely extending wall 85 14 and the longitudinally extending side walls 15, the rear wall being illustrated as mounted upon the rearwardly projecting ends of the guide strips 11. At the forward end of the table 10, opposite each guideway, 90 there is provided a button 16, which, when turned to a vertical position, prevents the discharge of coins from the guideway, but which when turned into a horizontal position permits such discharge.

Operatively supported in connection with each guideway *a*, *b*, *c* or *d*, is a coin holder. These coin holders are all alike in construction. Each holder is designated 17. Each holder is formed at the bottom edge with a 100 transversely extending plate 18, which is adapted to engage in the grooves 13 of the guide strips 11. Each holder at its lower end is reduced in width so as to travel between the guide strips and above the guide strips rests upon the upper faces of the strips, as illustrated best in Fig. 3. These coin holders 17 are adapted to be reciprocated along the guideways, and preferably 105 the upwardly and rearwardly inclined face 110

of each holder is formed with a stud, button or handle 19, whereby the holder may be reciprocated.

Each holder adjacent its rear end is formed with a coin receiving chamber 20 vertically disposed and open at its top and bottom, this chamber being of a size suitable to receive the particular coins disposed in the holder, but permits said coins to move downward by gravity. The plate 18 is, of course, also formed with an opening 21 beneath the chamber 20 through which the coins are discharged. The coins are stacked one upon another within the chamber 20 and fed downward therethrough by gravity. Disposed rearward of the chamber 20 is a stop 22 illustrated as in the form of a screw pin having a nick at its lower end so that the screw pin may be adjusted. The screw pin is so adjusted that its lower end is just above the upper face of the table or base 10 but extends down below the upper face of the lowermost coin of the stack of coins. Immediately in advance of the chamber 20 there is provided an adjustable stop pin 23, which is also screw-threaded and nicked at its lower end so that it may be adjusted and this screw pin is so adjusted that it will escape the lowermost coin of the stack of coins. As illustrated, the plate 18 is spaced from the upper face of the table 10 a distance equal to two coins and hence the necessity of this pin 23. If the coins are thick, this pin 23 may be adjusted upward so as to increase the distance between the pin 23 and the face of the table 10 and if the coins are relatively thin, the pin may be adjusted downward to decrease the distance between the lower end of the pin and the table 10, in a manner which will be obvious from the drawing. It will be seen, of course, that the cross bar 14 forms a stop limiting the rearward movement of the various coin holders.

In order to indicate to an operator the amount of coins desired to make change, certain of the longitudinally extending strips 11 are provided with graduations. Thus the longitudinal strip 11 which divides the guideway *a* from the guideway *b* is provided with numerals 5 and 10 spaced from each other and with arrows pointing toward the guideway *a* and it will be seen that between the numeral 5 and the end of the guideway, there are 5 pennies and between the numeral 10 and the end of the guideway, there are 10 pennies. The guide strip 11 which divides the guideways *c* and *b* from each other has arrows pointing to the guideway *b* and is provided with the numerals 25 and 50 and it will be seen that there are five 5 cent pieces disposed between the end of the guideway and the numeral 25 and ten 5 cent pieces disposed between the end of the guideway and the numeral 50. The strip 11 which divides the guide-

way *c* from the guideway *d* is provided with numerals 50 and \$1.00 with arrows pointing toward the guideway *c* wherein are disposed ten cent pieces and the marginal guide strip 11 has arrows indicating \$1.00 worth and \$2.00 worth of coins. Any other graduations, of course, may be used and these are merely illustrative.

In the operation of this device, assuming that the guideways are all empty, then one of the holders 17 is shifted forward, the corresponding button 16 being turned to permit this movement, and the pin 21 will slide the lowermost coin of the series of coins in the stack forward with the holder. Then when the holder is shifted rearward the coins will drop one after the other onto the table, the pin 23 preventing a superposition of the coins and when the holder has been shifted to its rearmost position, there will be a line of coins disposed one after the other along the face of the guideway, in the manner illustrated in Fig. 1. The same operation is performed with all of the holders until all the guideways are filled. Now when it is desired to make change or dispense a certain number of coins, the button on the particular guideway is turned down and coins are drawn out by hand, according to the graduation marks on the guideways. Assuming that twenty-five cents worth of five cent pieces have been withdrawn from the guideway *b*, then the operator shifts the holder of that guideway forward until the vacant space has been filled and then shifts the holder back to its rearmost position when the guideway will again be entirely filled with coins. As fast as the coins are exhausted from the chambers 20, new coins may be disposed in these chambers through the top thereof. As illustrated, each holder and guideway together will accommodate about 50 coins, but it is obvious that this capacity may be changed. It is, of course, obvious that this coin dispensing device may be made to hold dollars, five dollar gold pieces, etc.

Having described my invention, what I claim is:

1. A coin dispensing machine including a base having a coin guideway, a coin holder having a vertically disposed coin chamber opening at its lower end upon said guideway, means rearward of the coin chamber and mounted on the holder acting as a coin pusher, and means on the bottom of the holder for preventing the superposition of coins, and adjustable toward or from the bottom of the guideway.

2. In a coin dispensing machine, a table having a coin guideway formed therein, one end of the guideway being open for the discharge of coins, and a coin holder slidably mounted upon the table above said guideway and having a vertically extending coin

chamber within which coins are to be stacked, the chamber opening at its lower end upon said guideway, an adjustable stop pin mounted upon the under face of the holder rearward of the chamber and extending down into said guideway and adapted to engage the lowermost coin of the stack, and an adjustable stop pin disposed on the under face of the holder, forward of the coin chamber, and extending into said guide-
way and preventing the superposition of coins as the holder is shifted rearward along the table.

In testimony whereof I hereunto affix my signature in the presence of two witnesses. 15
